UNITED STATES PATENT OFFICE

DAVID WILSON WOOD, OF BRAZIL, INDIANA

KEEPER

Application filed May 3, 1932. Serial No. 608,993.

This invention relates to a device in the form of a latch bolt keeper, striker or retainer to be engaged by the bolt, and is a continuation in part of my pending allowed application Serial No. 540,112, filed May 26, 1931.

The device is designed and adapted to be used in conjunction with bolts or latches of different kinds, and is especially adapted for use in conjunction with a slidable bolt which is retained retracted and released for movement to a latching position by the operation of a retaining means upon the movement of the door to its closed position.

Other objects of the invention are the provision of a device of the indicated character having an abutment or striker which is adjustable when the bolt seats, thereby giving a perfect bearing between the bolt and the abutment or striker; the provision of an abutment or striker which is beveled to correspond to the bevel of the latching end of a bolt so that the bolt will not slip back or stick when disengaging the bolt to open the door; one which always holds the door tight and prevents vibration and rattling; one which compensates for disalignment of the door with its post or jamb by automatically adjusting itself to compensate for this variation or difference; and one which permits space in the keeper recess of the door jamb or post for the bolt to enter when the door is closed and the bolt is released thereby allowing the bolt to readily enter in contact with the abutment or striker, and at the same time overcoming the tendency of the door to fly open after reaching its closed position.

Another important object of the invention is the provision of a keeper of the indicated character which is useful in conjunction with the latch bolts carried by the doors of automobiles, the same being designed to avoid any undue strain from being imposed on the door or the latch caused by the twisting or weaving of the automobile body or frame to which the latching device is secured, and always allowing the latching device on the door to adjust itself to the keeper abutment or striker in the jamb or post.

The nature of the invention and its dis-

tinguishing features and advantages will appear when the following specification is read in connection with the accompanying drawing, in which

Figure 1 is a horizontal section showing a portion of a door and a portion of its jamb or post with the keeper of the present invention applied to the jamb, and the latch bolt of the latching device carried by the door being engaged with the abutment or striker of the keeper;

Figure 2 is a vertical section, the same being taken on the line 2—2 of Figure 1;

Figure 3 is a perspective view of the keeper detached.

Referring now more particularly to the several views of the drawing, it will be apparent by reference to Figure 1 that there has been shown, by way of example, a portion of an automobile door 10 and a portion of its jamb or post 11, and it being understood that the door swings on a vertical axis to its open and closed positions. The door 10 carries a suitable latching device which is disclosed in the aforesaid pending application. This latching device includes a latch bolt 12 which is mounted for sliding movement into and out of its retracted and latching positions.

The keeper of the present invention is secured in place on the jamb 11, and is positioned in a recess 13 in the jamb. The bolt 12 may enter the recess 13 when the door 10 is in its closed position. The keeper includes an abutment, striker, or retainer 14. This abutment 14 is mounted for universal rocking movement by reason of a semi-globular member 15 received on a seat 16 of an attachment 17 secured to the jamb 11 by fastening elements such as the screws 18. The abutment 14 is also yieldably supported by reason of a coil spring 19 surrounding a stem 20 on the member 15, the spring being disposed in contact with the attachment 17, and means 21 on the stem 20 in the form of a collar or washer held in place by a pin or the like. The abutment 14 is of tapering formation to present a contact face 22 beveled or disposed at an angle with respect to the longitudinal axis of the latch bolt. The bevel or

angularity of the face 22 corresponds to the engaging end of the latch bolt 12.

From the foregoing it will be apparent that the abutment 14 may be engaged by the bolt 12, and, by reason of its universal rocking movement and its yieldability, any slight displacement of the bolt 12 will be compensated by the ready adjustment of the abutment, affording all of the advantages hereinbefore set forth.

I claim:

1. A latch bolt keeper comprising an abutment to be engaged by the bolt, means mounting the abutment for universal rocking movement, and resilient means employed in conjunction with the first means to constrain the rocking movement of the abutment.
2. A latch bolt keeper comprising an attachment element, an abutment having a semi-globular member and stem on the rear side thereof, said element having a seat which receives said member, and a spring surrounding said stem and bearing against means on the stem and said element to rockably and yieldably support said abutment.
3. A latch bolt keeper including a rock-

able abutment having a beveled face to be engaged by a corresponding face of the latch bolt, and said abutment also having on its side opposite said beveled face a semi-globular member on which it rocks.

4. The combination with a door jamb, of a latch bolt keeper abutment, means mounting the abutment for universal rocking movement on said jamb, and resilient means employed in conjunction with said abutment to restrain the rock of the abutment.

5. The combination with a door jamb, of a latch bolt keeper abutment, means mounting the abutment for universal rocking movement on said jamb and positioned in a recess in the jamb, and resilient means employed in conjunction with said abutment to restrain the rocking of said abutment.

6. The combination with a door jamb, of a latch bolt striker plate member mounted for universal rocking movement on said jamb, and resilient means employed in conjunction with said plate member to restrain the movement thereof.

DAVID WILSON WOOD.
